GRINDING WHEEL RADIUS AND ANGLE
DRESSER

Robert E. Dahl, Cicero, Ill., assignor to Robra
Products Co., Cicero, Ill., a corporation of Illi-
nois

Application May 24, 1945, Serial No. 595,551

6 Claims. (Cl. 125—11)

1

My invention relates to grinding wheel radius and angle dressers, and more particularly to a device adapted to form abrasive wheels, such as grinding wheels, in any desired manner so that they may be employed in performing precision grinding or finishing work.

There are radius and angle wheel dressers in the prior art, but most of these are complicated and expensive.

One object of my invention is to provide a radius and angle wheel dresser of simple, sturdy and efficient construction whereby accurate abrasive wheel dressing may be performed in an expeditious, convenient and simple manner.

Another object of my invention is to provide a radius and angle wheel dresser of such simplicity that it may be manufactured cheaply and thus supply an important tool to industry at a reasonable cost.

Other and further objects of my invention will appear from the specification.

In the accompanying drawings, which form part of the instant specification and which are to be read in conjunction therewith, and in which like reference numerals are used to indicate like parts in the various views,

Figure 1 is a perspective view of my grinding wheel dresser;

Figure 2 is a side elevation of the device shown in Figure 1;

Figure 3 is a front elevation of my wheel dresser, showing the parts in position to form an angular face on the grinding wheel;

Figure 4 is a fragmentary view showing the motion of the diamond in dressing a convex radius on a wheel;

Figure 5 is a view similar to Figure 4 showing the motion of the diamond in forming a concave surface on the abrasive wheel;

Figure 6 is a view similar to Figures 4 and 5 showing the motion of the diamond in cutting an angular surface on the grinding wheel;

Figure 7 is a diagrammatic view showing the motion of the diamond forming a radius tangent to an angular surface on the grinding wheel;

Figure 8 is a sectional view taken along the line 8—8 of Figure 1;

Figure 9 is a fragmentary view taken along the line 9—9 of Figure 8;

Figure 10 is a sectional view taken along the line 10—10 of Figure 8;

Figure 11 is a sectional view taken along the line 11—11 of Figure 10; and

Figure 12 is a sectional view taken along the line 12—12 of Figure 8.

2

In general, my invention contemplates a suitable base of rigid construction adapted to be positioned adjacent the grinding or abrasive wheel to be dressed. Rotatively positioned on the base, is a slide guide member. My arrangement is such that the slide may be rotated through 360 degrees and calibrated means are provided to indicate the angle to which the slide is positioned. Mounted in the slide for adjustable movement, is a rotatable head carrying an arm in which the diamond is positioned. It is a feature of my invention that the arm extends beneath the grinding wheel. This offers several advantages: First, the wheel is trued at the bottom, which is the actual line of contact with the work with which the grinding wheel is used; secondly, with my wheel dresser, it is not necessary to move the safety guard from its position over the wheel, thus expediting the operation and guarding the workmen from possible injury. Furthermore, the table top on which the base is mounted is in a position closer to the wheel, reducing vibrations and making for accuracy, which is so important in high precision grinding. It will be appreciated that the precision of the final work can be no more accurate than that of the tool used to perform the work.

More particularly, referring now to the drawings, a base of any suitable construction is formed by a bottom plate 1, carrying a vertical or supporting plate 2. In the form shown in the drawings, the supporting plate 2 is secured to the bottom plate 1 by means of machine screws 3. The vertical or supporting plate 2 is provided with a notched portion 4 adapted to be used in connection with the calibrations formed on the rear surface of the guide 5. The guide is formed with a central hole and countersunk portion in which is positioned the head 6 of a bolt 7 which passes through an opening in the vertical plate 2. The end of the bolt 7 is formed with threads 8 engaging a nut 9 which may be provided with a knurled portion 12. The nut 9 acts as the stud bolt 7 handle and is provided with a skirt portion 10. Housed within the skirt portion 10, I provide a spring 11 adapted to frictionally position the slide stud head 6 against free rotation. Screwing the nut 9 on the threads 8, clamps the guide 5 between the stud head 6 and the vertical plate 2. The guide member 5 is provided with a dovetail groove in which a slide member 13 is positioned for longitudinal movement within the guide. A set screw 14 is provided for securing the slide member in any given position. Secured to the

ends of the guide member 5 by machine screws 15 and 16, are a pair of closure members 17 and 18. The closure members carry positioning screws 19 and 20. The function of these positioning screws is to govern the amplitude of motion of the slide member 13. A hub 21 is fixedly secured to the slide member 13 by means of machine screws 22 and 23. Clamped between the hub 21 and the slide 13 by the screws 22 and 23, is a dust plate 24, as can readily be seen by reference to Figure 11. Rotatably carried by the hub 21 is a revolving head 25. The head 25 is provided with a plurality of peripheral openings 26 adapted to receive a head handle 27. The head handle may be inserted in any suitable manner into any of the openings 26. If desired, the openings may be internally threaded and the handle may be provided with a threaded portion for coaction therewith, and obviously a plurality of handles may be used if desired. The lower portion of the revolving head 25 is formed with a slot into which one end of the diamond-holding arm 28 is adapted to be positioned by means of a screw 29. The screw 29 is annular in form and is internally threaded to receive a set screw 44. The end of the arm 28 is provided with a pivoted clamp 30 which, through clamping screw 31, is adapted to secure the diamond holder 32 in any desired position. The diamond holder 32 carries a diamond 33, or other suitably hard cutting point, depending on the nature of the abrasive wheel to be dressed. The diamond holder 32 is provided with calibrations 34 adapted to coact with the upper surface of the arm 28.

In operation, if it be desired to dress the grinding wheel 35 with an angular surface such as shown in Figure 6, the guide 5 is adjusted to the desired angle by means of the calibration 36 formed on the back of the guide member 5 coacting with the notch 4. To perform this adjustment, the nut 9 is first loosened, permitting the guide member 5 to be rotated around the stud head 6. If extreme accuracy is required, the angle of adjustment may be checked by means of an angle gauge through the surface 37 formed on the bottom of the guide 5. The base 1 is then in position adjacent the grinding wheel 35, and secured in any desired manner as, for example, by a magnetic surface plate, clamp or the like, known to the art. The parts will be in the position shown in Figure 3. The set screw 14 is then loosened, and the stop screws 19 and 20 are adjusted to give the desired amplitude of motion across the face of the grinding wheel. The rotatable head 25 is then adjusted to any desired angle such as one at which arm 28 is below hub 21 and the diamond point 33 is in alignment vertically with the axis of hub 21. This adjustment is facilitated by the calibrations 38 formed on the surface 39 of the rotatable head 25. A suitable reference point 40 is formed on the surface 41 of the hub 21. The head 25 is set in this position against rotation with respect to the hub 21 by means of the set screw 44 which is positioned in the annular securing screw 29. A suitable bushing member 42 may be provided to prevent marring the smooth bearing surface 43 of the hub 21. A handle 27 is then inserted in an appropriate opening 26. The diamond 33 is then adjusted, by means of the clamp 30 and the clamping screw 31, to the desired working position. The grinding wheel is then rotated and the slide 13 is reciprocated in the guide member 5 through the handle 27, manually, through the amplitude of motion determined by the stop

screws 19 and 20. The resultant motion is shown diagrammatically in Figure 6.

If it be desired to form a convex surface on the grinding wheel, this may be easily achieved by means of my invention, either tangent to a horizontal or angular surface. For example, if a convex surface, such as shown in Figure 4, is desired on the grinding wheel, tangent to a horizontal surface, the guide member 5 is set horizontally by means of the calibrations 36, in the manner described above. The set screw 14 is positioned to prevent motion of the slide 13. The diamond is positioned below the axis of the hub 21 to produce a convex surface. The radius of the surface is determined by the distance between the axis of the hub 21 and the diamond. This radius may be set by means of the calibrations 34 on the diamond holder, or by means of gauges if desired. The dresser is positioned as before, adjacent the grinding wheel to be dressed. The set screw 44, however, is retracted to permit the rotating head 25 to rotate freely, and the diamond point is moved along a locus describing the desired radius and by means of the handle 27. It is in such operations as this that the calibrations 38 find their main use which is to indicate the amount of arc travel of head 25 and facilitate obtaining the desired amount when describing a radius, for example by indicating the proper setting of arc travel stops.

A concave grinding surface may be formed on the abrasive wheel, such as shown in Figure 5, in the manner described above. It is to be noted, however, that in this case the diamond point is above the axis of the hub 21.

It will be obvious to those skilled in the art that my dresser may be used to form any combination of surfaces or any desired contour on the grinding surface of the abrasive wheel by a plurality of successive dressing operations. In Figure 7, for example, a curved surface having a desired radius tangent to an angular surface is shown.

It will be seen that I have accomplished the objects of my invention. I have provided a radius and angle dresser of simple and cheap construction which, nevertheless, may be employed to perform accurate operations necessary for precision grinding. The arrangements of parts are such that they may be speedily and accurately employed with safety to the operator. I may employ my device to perform a radius which is tangent to a surface having any given angle with the vertical, an operation heretofore very difficult by any of the means of the prior art. Once my dresser is positioned, a simple motion by the operator performs the accurate dressing, thus making for extreme accuracy and speed and ease of work. The simplicity of set-up, coupled with the ease of operation, presents advantages not found in existing dressers. My dresser is designed to true the grinding wheel from the bottom because this is the line of contact with the work when the grinding wheel is being used to perform its grinding operation. Furthermore, it is not necessary to move the guard from its position over the grinding wheel. It will be observed further that a table adjacent the grinder may be positioned relatively close to the grinding surface of the grinding wheel, thus making for greater accuracy by eliminating possible vibration.

It is obvious that changes may be made in the particular construction shown and described without departing from the spirit of my invention. It is therefore to be understood that I do

not wish to be limited to the particular details shown and described except as stated in the appended claims.

Having thus described my invention, what I claim is:

1. An angle and radius dresser for abrasive wheels including in combination a base, a guide rotatably mounted on said base for angular adjustment from a horizontal position to any desired angle including a straight angle, means for releasably securing said guide in any such angular position of adjustment, a member slidably mounted on said guide for movement between limiting positions on opposite sides of the axis of rotation of said guide, releasable means for locking said member in any position within said limits of movement, a head rotatably supported by said slidable member and rotatable with respect to said member about an axis extending parallel with the axis of rotation of said guide, a cutting tool, means carried by said head for supporting said cutting tool, and means for releasably locking said head against rotation relative to said slidable member in any angular position to which said head is rotated.

2. An angle and radius dresser for abrasive wheels including in combination a base, a guide rotatably mounted on said base for angular adjustment from a horizontal position to any desired angle including a straight angle, means for releasably securing said guide in any such angular position of adjustment, a member slidably mounted on said guide for movement between limiting positions on opposite sides of the axis of rotation of said guide, releasable means for locking said member in any position within said limits of movement, a head rotatably supported by said slidable member and rotatable with respect to said member about an axis parallel with the axis of rotation of said guide, a pointed dressing tool, an arm carried by said head and extending therefrom substantially parallel to the axes of rotation of said head and guide, means mounting said tool on said arm for adjustment relative thereto to position the point of said tool on one side or the other side of the axis of rotation of said head.

3. An angle and radius dresser for an abrasive wheel comprising a support, a stud extending from said support, a block journalled on said stud for angular adjustment about the axis thereof to any desired angle, said block having a guideway therein, a slide block mounted in said guideway for movement therealong during dressing of the angle surface corresponding in inclination to the angle of adjustment of the first mentioned block about the axis of the stud, a second stud projecting from said block and having its axis parallel to the axis of the first mentioned stud, a disc mounted on said second stud for angular movement to any desired angle, an arm secured to said disc and extending therefrom substantially parallel to the axis of said studs, a dressing tool, means for adjustably mounting said tool on said arm for adjustment transverse to the axis of rotation of said disc to one or the other side of said axis, means for releasably locking said slide block against slidable movement in any desired position spacing the axis of the second stud a predetermined distance from the axis of the first mentioned stud, and means for locking said disc in any angular position of adjustment about the axis of the second stud.

4. An angle and radius dresser for an abrasive wheel comprising a support, a stud extending from said support, a block journalled on said stud

for angular adjustment about the axis thereof to any desired angle, said block having a guideway therein, a slide block mounted in said guideway for movement therealong during dressing of the angle surface corresponding in inclination to the angle of adjustment of the first mentioned block about the axis of the stud, a second stud projecting from said block and having its axis parallel to the axis of the first mentioned stud, a disc mounted on said second stud for angular movement to any desired angle, an arm secured to said disc and extending therefrom substantially parallel to the axes of said studs, a dressing tool, means for adjustably mounting said tool on said arm for adjustment transverse to the axis of rotation of said disc to one or the other side of said axis, means for releasably locking said slide block against slidable movement in any desired position spacing the axis of the second stud a predetermined distance from the axis of the first mentioned stud, means for locking said disc in any angular position of adjustment about the axis of the second stud, and means for releasably locking the first mentioned block in any angular position of adjustment about the axis of the first stud.

5. An angle and radius dresser for an abrasive wheel comprising a support, a stud extending from said support, a block journalled on said stud for angular adjustment about the axis thereof to any desired angle, said block having a guideway therein, a slide block mounted in said guideway for movement therealong during dressing of the angle surface corresponding in inclination to the angle of adjustment of the first mentioned block about the axis of the stud, a second stud projecting from said block and having its axis parallel to the axis of the first mentioned stud, a disc mounted on said second stud for angular movement to any desired angle, an arm secured to said disc and extending therefrom substantially parallel to the axes of said studs, a dressing tool, means for adjustably mounting said tool on said arm for adjustment transverse to the axis of rotation of said disc to one or the other side of said axis, means for releasably locking said slide block against slidable movement in any desired position spacing the axis of the second stud a predetermined distance from the axis of the first mentioned stud, means for locking said disc in any angular position of adjustment about the axis of the second stud, and means for releasably locking the first mentioned block in any angular position of adjustment about the axis of the first stud.

6. An angle and radius dresser for an abrasive wheel comprising a support, a stud carried by and projecting from said support, a first block journalled intermediate its ends on said stud for angular adjustment about the axis of the stud to any desired angle, said block having a guideway therein extending transverse to the axis of said stud on opposite sides thereof, a second block slidably mounted in said guideway for movement therealong from one to the other side of the axis of said stud, a second stud carried by said slide block and projecting therefrom with its axis substantially parallel to the axis of the first stud and movable with said slide block to position the axis of the second stud eccentric to the axis of the first stud on one side or the other side of the axis of the first stud, a collar mounted on said second stud for angular movement through and desired

angle, an arm secured to said collar and projecting therefrom parallel to the axes of said studs, a dressing tool, means for adjustably mounting said dressing tool on said arm for adjustment transverse to said axes to position the working surface of the tool on one side or the other side of the axis of the second stud, releasable means for locking said first block in any angular position of adjustment about the axis of the first stud, means adjustably carried by the first block for engaging and limiting movement of the slide block in one direction with respect to the axis of the stud, means adjustably carried by the first block for engaging and limiting movement of the slide block in the opposite direction with respect to the axis of the first stud, releasable means for

5

locking said slide block in any position within its limits of movement, and means for releasably locking said collar in any angular position of adjustment about the axis of the second stud.
